UNITED STATES PATENT OFFICE.

JOSEPH W. JOHNSON AND JOHN W. NOLDE, OF NEWBURGH, NEW YORK.

COMBINED CURTAIN SUPPORT AND SHADE HOLDER.

Application filed November 1, 1921. Serial No. 511,991.

To all whom it may concern:

Be it known that we, JOSEPH W. JOHNSON and JOHN W. NOLDE, citizens of the United States, residing at Newburgh, in the county of Orange and State of New York, have invented certain new and useful Improvements in Combined Curtain Supports and Shade Holders, of which the following is a specification.

10 This invention relates to combined window shade and curtain supports.

The object of the invention is to provide a device of this character which may be adjusted to fit windows of different sizes and 15 which may be secured to the window frames with one set of fasteners avoiding marring of the frame.

Another object is to provide a support of this character which may be constructed 20 from sheet metal strips so that it may be manufactured with a minimum amount of material at a small cost and will be light, strong and durable in construction.

With these and other objects in view, the 25 invention consists in certain novel features of construction as hereinafter shown, described and claimed.

In the accompanying drawings:—

Figure 1 represents a perspective view of 30 the upper portion of a window frame with this improved support shown applied.

Fig. 2 is a top plan view of the support detached, the top broken out for convenience in illustration.

35 Fig. 3 is a transverse section taken on the line 3—3 of Fig. 2, and,

Fig. 4 is a front elevation with parts broken out and in section.

The support or hanger constituting this 40 invention comprises three sections 1, 2 and 3, the sections 1 and 3 being designed to be mounted on the sides of the window frame shown at F and which are connected by the intermediate section 2 in a manner presently to be described.

The sections 1 and 3 are made exactly alike except that they are right and left, one being designed to be secured to the right hand side of the window frame and the 50 other to the left hand side, and hence it is thought necessary to describe one only in detail.

The frame engaging section 1 is composed of an L-shaped member 4 and a straight member 5 adjustably connected by a slide 55 6 to adapt the section to fit window frames

of different depths. The straight section or member 5 has an outwardly bowed portion 7 near its outer end which is apertured as shown at 8 to receive a shade roller pintle 60 and on opposite sides of said bowed portion, the member 5 is apertured as shown at 9 to receive fastening elements for securing the sections to the window frame. The members 4 and 5, as well as the other portions of the hangers are constructed of strap metal. One arm 10 of the member 4 is designed to lie against the outer face of the window frame as is shown clearly in Fig. 1, and has its free end folded inwardly 70 as shown at 11 to form a socket to receive an upstanding strip 12 which is riveted or otherwise secured in said socket. This upstanding member 12 is also constructed of strap metal and is designed to support one 75 end of section 2 which constitutes the curtain holder. The upright member 12 may be of any desired length according to the height it is desired to space the section 2 above sections 1 and 3 and has its upper 80 end folded downwardly and then upwardly to form a seat 13 to receive one end of section 2 as will be presently more fully described.

Section 2 which is supported at its opposite ends in the upstanding members 12 of the side frame engaging sections 1 and 3, is composed of two members 14 and 15 with the inner end of one lapping that of the other and slidably connected by slides 90 16 to provide for the adjustment of the members 14 and 15 longitudinally relatively to each other to adapt a hanger to fit window frames of different widths.

The members 14 and 15 are exactly alike 95 except that one is the right and the other the left hand member and each is composed of a strip of metal with its outer end bent into substantially U-shaped form with the terminal 17 thereof adapted to be inserted in 100 the seat 13 of one of the upstanding members 12. The U-shaped formation of the outer ends of the members 14 and 15 spaces the body portions thereof in advance of the sections 1 and 3 and by the adjustment of 105 the members 4 relatively to the members 5, the side sections 1 and 3 and section 2 may be positioned toward and away from the window frame at the will of the user so that the curtain suspended therefrom may be 110 hung at any desired distance from the window frame. It is of course understood that

the U-shaped members at the ends of the sections 14 and 15 are turned inwardly toward each other as is shown clearly in Fig. 2.

5 The detachable connection of the end members 14 and 15 of section 2 to the frame engaging sections 1 and 3 provides for the disassembling of the parts and their storage in a small space when to be shipped or 10 stored.

In the use of this hanger, the only fasteners necessary for securing it to the frame are those which are inserted through the apertures 9 of the members 5 of 15 sections 1 and 3, and when they are so connected and the members 4 adjusted on members 5 so their arms 10 engage the outer faces of the frame, they will be securely held with the employment 20 of a minimum number of fasteners and thereby avoid marring of the frame as much as possible.

The preferred embodiment of the invention is disclosed in the drawings and set 25 forth in the specification, but it will be un-

derstood that any modifications within the scope of the claimed invention may be made in the construction without departing from the principle of the invention or sacrificing any of its advantages.

We claim:

A bracket comprising a frame engaging section consisting of an L-shaped member forming an inner and an outer arm, a rearwardly extending supporting member having an apertured bow-shaped portion intermediate its ends and an apertured inner terminal, means for slidably connecting said supporting member to said inner arm, said outer arm having its outer terminal portion 40 folded upon itself, a vertically disposed member secured between said folded outer terminal portion and having its upper terminal portion bent upon itself to provide a support for the reception of one end of a 45 curtain support.

In testimony whereof, we affix our signatures hereto.

JOSEPH W. JOHNSON.
JOHN W. NOLDE.
